Primary Examiner — Cathron C Brooks*Assistant Examiner* — Samantha Q Lawrence*(74) Attorney, Agent, or Firm* — Heedong Chae; Lucem, PC(57) **CLAIM**

The ornamental design for a sanitary pad, as shown and described.

DESCRIPTION

FIG. 1 is a front perspective view of a sanitary pad showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front perspective view of the sanitary pad with wings in an open position.

The broken lines shown in FIGS. 1-9 illustrate portions of the sanitary pad that form no part of the claimed design.

1 Claim, 8 Drawing Sheets---
